CLAIM

The ornamental design for a solar cell with via, as shown and described.

DESCRIPTION

This application is related to U.S. patent application Ser. No. 29/497,816 filed Jul. 29, 2014, U.S. patent application Ser. No. 29/583,112, filed Nov. 2, 2016; U.S. patent application Ser. No. 29/584,652 filed Nov. 16, 2016; and U.S. patent application Ser. No. 29/586,506 filed Dec. 5, 2016.

FIG. 1 is a top perspective view that illustrates the solar cell with via showing our new design;

FIG. 2 is an enlarged fragmental view taken from the designated area in FIG. 1;

FIG. 3 is a top plan view of FIG. 1;

FIG. 4 is a bottom plan view thereof;

FIG. 5 is a rear side elevation view thereof;

FIG. 6 is a front side elevation view thereof;

FIG. 7 is a left side elevation view thereof;

FIG. 8 is a right side elevation view thereof; and,

FIG. 9 is an enlarged fragmented view taken from the designated area in FIG. 7.

The dash-dot-dot broken line portion of the figure drawings is included to show boundaries and form no part of the claimed design. The broken line portion of the figure drawings is included to show portions of the article that form no part of the claimed design.
